SOUND REPRODUCING FILM AND A DEVICE
FOR RECORDING SOUNDS PHOTOGRAPH-
ICALLYArnold Poulsen and Axel Carl Georg Petersen,
Copenhagen, DenmarkApplication January 25, 1932, Serial No. 588,792
Renewed February 17, 1937. In Germany Feb-
ruary 26, 1931

4 Claims. (Cl. 274—41.6)

In the reproduction of tones (sound oscillations) recorded on films it is well known that a more or less prominent tingling or crackling, the so-called back ground noise is produced. Part 5 of this noise may originate from the microphone or amplifier used in the recording, or from the light-sensitive cell or amplifier used in the reproduction process. By careful construction, however, of the amplifier, the microphone and the light-sensitive cell the background noise due to 10 these parts may be reduced to a very small value.

In addition to the above mentioned causes the background noise may originate from irregularities of or impurities in the layer of emulsion on 15 the film, or from so-called scratches in the same, which unavoidably are produced by wear. The prominence of noise due to the last mentioned causes depends on the transparency of the sound reproduction film after it has been developed and fixed. Scratches and irregularities in the emulsion coating of the film will therefore greatly 20 manifest themselves as background noise, when a relatively large part of the sound films used for the reproduction is translucent.

The background noise originating from the emulsion irregularities and from the scratches in 25 the film is generally independent of the magnitude of the sound amplitudes and, consequently, becomes more prominent with decreasing amplitudes, so that this noise is especially noticeable 30 during the tone pauses.

In the reproduction of sounds made from photographic sound records of the variable density type the background noise may be consider- 35 ably reduced by decreasing the average degree of density of the negative film with decreasing sound amplitude and, consequently, the corresponding density of a positive film, i. e. a repro- 40 ducing film copied from said negative film in any ordinary manner will increase with decreasing sound amplitude. The transparency of the re- 45 producing film will be reduced when the sound amplitudes decrease, and the background noise will then be reduced at the same rate.

The average density of the film does not neces- 45 sarily have to be varied during the sound record- 50 ing itself. An ordinary negative or positive sound film of the variable density type, on which the sound has been recorded in the usual manner, may be used and a new positive or negative film pro- 55 duced therefrom by conversion of the sound re- 60 corded on the original negative film into corre- 65 sponding electric currents, by means of which the sound is recorded on the new film with varia- 70 tion of the average density of the film.

The above mentioned variation of the average density of the photographic film is equivalent to a displacement of the working point on the so-called blackening curve of the light sensitive layer of the film—i. e. or a curve representing 5 diagrammatically the dependency between the intensity of the exposure of the film and the corresponding degree of blackening of the developed film. This displacement is effected so that a portion 10 of the varying electric current, into which the sound is converted for the purpose of being recorded, is in known manner rectified and caused to act on the zero-position of the sound recording member, i. e. the position about which the said member oscillates during the recording— 15 or on the mean value of the sound recording bundle of rays—i. e. the value about which the intensity of the bundle of rays of light is varying in accordance with the sound oscillations.

It will be suitable according to the invention 20 to govern the sound-recording member (the light or the light projecting system) in such a manner that at increasing sound amplitudes the said rectified current will increase and consequently the displacement of the working point on the black- 25 ening curve will occur just as quickly as or quicker than the latter sound amplitudes increase and, vice versa, at decreasing sound amplitudes the said displacement will be effected more slowly 30 than the amplitudes decrease.

It will be seen that as a result of this arrange- 35 ment a sound produced suddenly after a pause—as most sounds are—will cause a corresponding displacement of the working point as quickly as, or more quickly than the increase in the magni- 40 tude of the sound amplitude concerned, away from the position occupied by the working point during the pause—which generally will mean the position corresponding to full blackening of the sound-record track.

The sound concerned will therefore be recorded 45 with certainty, and when a sound dies slowly away the density will vary so slowly that it can- 50 not reach the maximum value during the pauses, before the audible oscillations to be recorded have ceased.

This adjustment of the controlling system for 55 a sound-recording member can be attained simply by mutual adjustment of the coefficients of con- 60 ductivity for the circuit or one or more of the cir- 65 cuits, by way of which the above mentioned recti- 70 fied current is transferred to or is caused to actuate the sound-recording member. This is accom- 75 plished in such a manner that the variations in 80 the rectified current are effected more quickly 85 55

when the said current increases than when it decreases.

Usually, a rectifier valve is used for rectification of the above mentioned current and the control may be effected by inserting in the anode circuit of the rectifier valve a smoothing condenser connected in parallel to an ohmic resistance. The value of the resistance is so adjusted depending on the ohmic resistance of the rectifier valve, that on the 10 charging of the condenser during the passage of a positive half wave through the rectifier valve will be effected more quickly than the subsequent discharge of the condenser during the occurrence of a negative half wave.

15 The details of the invention appear from the following description of the same in connection with the drawing showing curves and diagrammatic constructions of recording systems according to the invention.

20 Fig. 1 shows the blackening-curve of a negative tone film and the position of the working point on this curve, for recording sounds according to the present invention.

25 Fig. 2 shows diagrammatically, a system constructed, according to the invention, for exposure of a film during recording of tones (sound oscillations) thereon according to the varying intensity method.

30 Fig. 3 shows in front elevation, an exposure slit used in this system, and

Fig. 4 shows a system for controlling the recording member in such a manner that the working point of the blackening curve is removed farther away from a given initial position the greater the 35 tone amplitudes are.

Fig. 5 diagrammatically represents the shifting of the zero line during the increase and decrease of the sound amplitude;

Fig. 6 is an outline of a variable width record 40 prepared in accordance with the present invention;

Fig. 7 represents the variable width record prepared in accordance with the invention; and

Fig. 8 represents a variable density record 45 corresponding to the one shown in Fig. 7.

In Fig. 1 *a* is the blackening-curve for instance for a silver-bromide emulsion applied to a negative film. The abscissae *J* represent the intensities of lighting, and the ordinates *S* represent the 50 degrees of blackening measured as a percentage of the maximum density, which latter corresponds to complete opaqueness of the light-sensitive coating, after this has been developed and fixed.

55 When recording sounds according to the well-known variable density process, the point *c* of the blackening-curve, at which the work is being performed, i. e. the point on the curve on both sides of which the blackening varies uniformly during 60 recording, is a fixed point of the curve, irrespective of the magnitude of the tone amplitudes.

As shown in Fig. 1, the point *c* is situated at a 65 relatively low point on the curve *a*—ordinarily at the central point of the rectilinear portion of the curve *a*—so that on the negative film the sound records corresponding to sound oscillations of smaller amplitudes appear relatively very opaque. Accordingly on a positive film copied from the negative film the portion of the record representing 70 sounds of smaller amplitudes will be relatively very translucent, whereby the background noise will manifest itself greatly and will increase with decreasing sound amplitudes. In order to avoid this according to the invention during the sound 75 pauses the working point *c* should be situated on

the lower part of the curve at *o*. During recording the point *o* travels towards the centre *c* of the blackening curve when the sound amplitude increases.

Disregarding temporarily the ordinary variations in the exposure due to the variations of the amplitudes of the sounds and considering only the varying average lighting of the negative film during the recording of sound oscillations of various amplitudes, then it will be seen directly that the light passing through the negative film during the printing of the same will vary from about 100% to about 50%, or, as the point *o* is not situated quite as far down as the initial point of the curve *a*, from for instance 90% corresponding to the point *o* and to about 50% corresponding to the central point *c* of the rectilinear or nearly rectilinear part of the negative blackening curve.

By "blackening" in the present specification is meant not what is ordinarily understood by this word. If the blackening is indicated by *S* and the amount of light impinging on a certain area of the film is indicated by *I* and the portion of said light penetrating or passing the film is indicated by *P*, then

$$S = 1 - \frac{P}{I}$$

or

$$S = \frac{I - P}{I}$$

Now, *I*—*P* is the amount of light which has been absorbed by the film and if this amount is indicated by *A* then

$$S = \frac{A}{I}$$

i. e., *S* is the ratio between the amount of light impinging on the film and the portion of said light which is absorbed by the film. In Fig. 1 of the drawing *S* is a percentage of *I*.

When recording sound oscillations on films according to the variable density method, the sound, as is well-known, is converted into varying electric current, which is caused to act upon a system by means of which the film is exposed in such a manner that the intensity of exposure of the film is modified in accordance with the current. In Fig. 2 a system of this nature is illustrated, in which an oscillating mirror *e* is used which is supported by an oscillograph loop *f* and is exposed, through a slit *g* in a screen *h*, to a source of light *i* an image of which is formed in the plane of the mirror by means of a lens *n*. The mirror projects an image *g'* of the slit *g* on to a screen *l* disposed between the mirror and the film *k*, in such a manner that the image *g'* partly covers a slit *m* in the screen *l*. A cylindrical lens *n* produces on the film *k* a linear image *i* of the image of the source of light formed on the mirror by the lens *n*.

Assuming that the mirror swings about the longitudinal axis of the loop *f*, the image *g'* will be caused to cover alternately more or less of the slit *m* and, consequently, the part of the bundle of light reflected from the mirror *e* and passing through this slit will vary in accordance with the oscillations of the mirror. In other words, the quantity of light concentrated on the film *k* by the lens *n* and, consequently, the light intensity of the image *i* will vary in accordance with the 70 oscillations of the mirror.

According to the well known variable density recording processes, the mirror, when at rest occupies such a position that one edge of the image *g'* coincides approximately with the center line *q*

of the slit m . According to the present invention the mirror e is so adjusted that the edge of the image g' , when the mirror is at rest, is not at the center line q but at or quite near to the bottom edge q' of the slit m , so that the intensity of the lighting on the film will correspond to the point o of the curve a , Fig. 1. When sound oscillations act on the sound-recording device, then the edge of image g' that originally was situated along the edge q' has to pass the edge of the slit m to an extent increasing with the amplitudes of the sound oscillations, in correspondence with the above described fact that the point o has to be displaced on the curve a .

This displacement may, for instance, be effected in the manner illustrated in Fig. 4, in that a portion of the current, into which the sound is converted for the purpose of being recorded, is directed across a transformer T' to a rectifier valve s , in which the current is rectified and amplified, and then directed across a resistance t inserted in parallel with a condenser u in the anode circuit of the valve s . The anode current of the valve s produces voltage variations across the resistance t , which are impressed upon the grid of an amplifier valve v . The anode circuit of this amplifier valve v is closed by way of the oscillograph loop f , Figs. 2 and 4, to which the secondary winding of a transformer T is connected, and by way of which transformer the alternating current, into which the sound is converted for the purpose of being recorded, is transferred to the loop f .

It will thus be seen that the working position occupied during recording by the oscillograph loop f and, consequently, by the mirror e will depend on the anode current of the valve v , while the periodic oscillations that the mirror has to perform in order to be able to record the sound will depend on the alternating current supplied by way of the transformer T of the loop. The initial voltage on the grid of the valve v is selected in such a manner that a relatively high plate current will flow in the valve v when the current rectified by the valve s is small, i. e. when the sound oscillations occurring are weak. The mirror e is then rotated at a relatively wide angle, for example to such an extent that the edge of the image g' will be situated only slightly inside 50 of the bottom edge of the slit m .

The exposure of film k is therefore very weak, corresponding to a very considerable blackening of a positive film produced by copying from the film k . When the sound amplitude increases, then the current rectified by the valve s will also increase, and the drop of voltage across the resistance t will reduce the initial grid voltage in the valve v , whereby the anode current of the latter will be reduced. The mirror is thus turned 60 so that the image g' will be moved further across the slit m .

In the above it was assumed that the edge of the image g' , when the mirror is at rest, is situated at the bottom edge of the slit m or only 65 slightly below the same. When the edge of the image g' is situated appreciably inside of the bottom edge of the slit or entirely outside the slit m at the bottom edge of same, then there will be no recording of noise of too small amplitude to 70 produce rectified current of a magnitude sufficient to turn the mirror to such an extent that the image g' will be moved inside the slit m . This result may be attained simply by adjusting the plate current of the tube v so that the image g' 75 is not allowed to enter the slit m unless the actu-

ating impulses surpass a certain minimum value.

In the above the assumption was that the displacement of the working point o was proportional to the amplitude of the sound.

With no direct current from the anode circuit of the valve v passing through the loop f , the mirror is adjusted to such a position that the amount of light passing the aperture m is sufficient to expose the film to a degree corresponding to a density of 50 per cent. The valve v is 5 then switched into circuit and the anode current is adjusted to such a value that when passing through the loop f , the mirror is moved to the position in which the upper edge of the cross-section of the light beam g^1 is at the lower edge 10 of the aperture m . When the intensity of the sounds to be recorded reaches a maximum, the current from the rectifier s will be a maximum thus causing a maximum negative biasing potential to be applied to the grid of the valve v . The 15 plate current of that valve will thus become zero. At values between zero and the maximum value of plate current in the valve v , it will be understood that the light beam g^1 will take up corresponding positions in relation to the aperture m . 20

As already stated, it is preferable that the mean density of the record corresponding to the loudest sound to be recorded should be not greater than 25 50%. To avoid distortion of loud sounds, the apparatus will in any case be so designed that, 30 at an assigned maximum sound intensity, the total extent of the oscillation of the edge of the cross-section g^1 of the beam of light, consequent on the sound vibrations, is not greater than the width of the aperture m , and it is only necessary, 35 to obtain the above result, that the maximum (or initial) value of the continuous current flowing in the anode circuit of the valve V shall be not greater than the maximum peak value of 40 the alternating current in the secondary winding of the transformer, and that the continuous current shall be zero at the assigned maximum sound intensity. If these conditions are satisfied it will be evident that the mean position of the edge of 45 the beam of light will be at or near the middle of the aperture m when the assigned maximum sound intensity is reached. It is to be noted that if this assigned maximum should be exceeded the mean position of the beam of light is not altered, 50 because the anode current has already been brought to zero. This would not be the case if the anode current were varied directly as the intensity of the sound, as in this case an exceptionally loud sound, would cause an exceptionally heavy anode current which might move the beam 55 of light off the aperture m altogether.

The nature of the sound record produced in accordance with the present invention will more clearly appear from Figs. 5-8.

In Fig. 5 the dotted line o represents the zero 60 line of an amplitude record. At the left side we have shown a few sound waves, the volume of which is suddenly increased from d to c and at the same time the zero line is displaced from the zero point x to the zero point x' . It is assumed 65 that prior to the increase the amplitude d of the waves is constant and that after the increase the amplitude c of the waves is also constant until it again decreases at the zero point x'' . The zero 70 line is shifted from the zero point x to the zero point x' in a period of time represented by the distance A measured in the direction of the movement of the film. This direction is indicated by the arrow P .

The variation of the amplitude of the regis- 75

tered variations, i. e., the difference $c \div d$, takes place within the period of time represented by A.

At the right-hand side of Fig. 5 we have shown what happens when the volume of sound decreases from the magnitude a (which is equal to c) to the magnitude b (which is equal to d). It is assumed that the variation $a \div b$ representing the decrease of the volume of the sound takes place during the time represented by A_1 , i. e., the horizontal distance between the two zero points x'' and x_4 .

If A_1 is equal to A and $c \div d$ is equal to $a \div b$, then $a \div b$ and $c \div d$, respectively, represent a variation of a certain magnitude ($a \div b$ or $c \div d$) 15 and at a certain rate (A or A_1). It will be clear that the zero point x' is not shifted back to a position x''' corresponding to the original position x within the period of time A_1 , but considerably more slowly, viz., in the course of the time 20 represented by B. The shift of the zero line caused by the increase is equal to $x' \div x$, and the shift of the zero line during the decrease and within the same period of time is equal to $x'' \div x'''$, and this shift is considerably smaller 25 in the transversal direction of the film than $x' \div x$. For the sake of simplicity it is assumed that the volume of the sound represented in the right-hand portion of Fig. 5 decreases from a to b in the course of two consecutive waves w and w_1 .

30 After this the volume b is kept constant.

Fig. 5 illustrates that in accordance with the present invention a certain variation of the volume of the sound is not only of a certain value ($a \div b$ and $c \div d$) with respect to the amplitude 35 variation, but also of the same value with respect to the time (represented by A and A_1 , respectively), within which said variation takes place.

A variable density record according to the invention is shown in Fig. 8. Since the graphical 40 identification of the invention is well-nigh impossible in such illustration, the variable width counterpart of this record is shown in Figs. 6 and 7. In practice such translation of variable width records into variable area records is effected by special equipment well known to those skilled in the art.

Fig. 7 shows the corresponding variable width record and Fig. 6 a line representing the corresponding sound. It will be noted in Fig. 6 that 50 the increase of the sound volume takes place at a considerably higher rate than the decrease of the volume of the sound. This is a natural phenomenon, and the zero line will, of course, always be shifted more rapidly towards the center line 55 of the film than towards the border line. However, two consecutive sound waves I and II may

be found the maximum amplitudes of which have a certain difference p , see Fig. 6, which is equal to the difference between two other consecutive sound waves occurring during the decrease of the sound, see the two waves III and IV in Fig. 6. 5 These two equal differences p appear within the same period of time A.

If the record is prepared in such a manner that the shift q of the zero position corresponding to the difference p during the increase of the sound, see the left-hand side of Fig. 7, is larger than the shift q_1 of the zero position corresponding to the difference p during the decrease of the sound volume, see the right-hand side of Fig. 7, then the record is made according to the present 15 invention.

In a variable density record the variations are indicated only by differences in scratching, and it is not possible in a scratching made by hand to indicate the differences in the average density by 20 a more open or narrow scratching without intermingling the average density and the minimum density of the different waves. Therefore Fig. 8 is only a crude illustration of the invention.

Having now particularly described and ascertained the nature of our said invention and in what manner the same is to be performed we declare that what we claim is:—

1. A sound record film the zero line of which shifts with amplitude changes in the sound, and 30 in which said shift occurs more rapidly when the sound volume increases by a certain value than when it decreases by said certain value.

2. A sound record film in which the mean density of the sound track varies between the 35 density corresponding to the central point of the rectilinear portion of the density characteristic of the said film and the density corresponding to one end of the rectilinear portion of the said characteristic.

3. A sound record film on which the average transparency of the sound track is shifted at a higher rate than the volume of the sound varies, when the said volume increases, and is shifted at a lower rate than the variation of the volume of 45 the sound, when the said volume decreases.

4. A sound record film in which the mean transparency of the sound track varies between the transparency corresponding to the central point of the rectilinear portion of the density characteristic of the said film and the transparency corresponding to one end of the rectilinear portion of the said characteristic. 50
